UNITED STATES PATENT OFFICE.

SAMUEL R. BAILEY, OF AMESBURY, MASSACHUSETTS.

SHAFT-SHACKLE FOR VEHICLES.

SPECIFICATION forming part of Letters Patent No. 703,364, dated July 1, 1902.

Application filed January 25, 1902. Serial No. 91,238. (No model.)

To all whom it may concern:

Be it known that I, SAMUEL R. BAILEY, a citizen of the United States, and a resident of Amesbury, in the county of Essex and State 5 of Massachusetts, have invented certain new and useful Improvements in Shaft-Shackles for Vehicles, of which the following is a specification.

This invention relates to improvements in 10 shaft-shackles for vehicles, and has for its object a device of improved and simplified construction capable of being readily applied to and detached from the clip.

My invention consists in the features and 15 in the construction and arrangement of parts hereinafter described, and definitely pointed out in the claims following the description, reference being had to the accompanying drawings, forming a part of the specification, 20 wherein—

Figure 1 is a front elevation of my improved shaft-shackle, showing the same applied to a thill-coupling of a vehicle-axle. Fig. 2 is a longitudinal section on the line 2 2 shown in Fig. 1. Fig. 3 is a detail front elevation of the inner end of the shaft-iron. Fig. 4 is a cross-section on the line 4 4 shown 25 in Fig. 2; and Fig. 5 is a detail rear view of the adjustable jaw, shown as removed from the 30 shaft-iron.

Similar letters refer to similar parts wherever they occur on the different parts of the drawings.

Referring to the drawings, A indicates one 35 end of a carriage thill or shaft secured in a suitable manner to the shaft-iron B.

The shaft-iron B is provided at its rear or 40 inner end with a preferably semicircular jaw b, which in connection with an adjustable pivoted preferably semicircular jaw C is adapted to encompass the thill-coupling bolt D or an elastic sleeve d, located thereon, as shown.

The bolt D is pivotally connected to the 45 ears E E of the clip E', which is secured to the carriage-axle F by means of the plate G and nuts e e, as is common in devices of this kind.

The rear inner face of the thill-iron B is 50 provided with a cylindrical recess b', and from the central bottom portion of such recess projects an externally-threaded stud or

screw b", which may be formed, preferably, integral with the thill-iron B, as shown, or may be attached thereto in any desired or 55 suitable manner.

The adjustable jaw C is provided at its inner end with a sleeve C', which is guided and longitudinally adjustable in the cylindrical recess b' in the shaft-iron B, as shown. 60 Within said sleeve C' is journaled a cylindrical nut H, which is internally screw-threaded, so as to engage the correspondingly-threaded screw-bolt b", as shown in Figs. 2 and 4. To the outer end of the internally- 65 screw-threaded nut or sleeve H is secured in a suitable manner an actuator H', preferably made in the form of a circular wheel or disk; but I wish to state that I do not desire to confine myself to this exact form or construction of said actuator or adjuster, as it may be made in the form of a lever or thumb-piece of any desired shape without departing from the essence of my invention. In practice I prefer to provide such actuator or 70 lever with one or more perforations h h, adapted to receive a strap I, preferably connected to the thill-coupling plate G by passing it through a slotted perforation g in the latter, as shown in Fig. 2, which strap serves, 75 when connected to the plate G and adjuster H', as a means to prevent the latter from rotation. The cylindrical nut H may be freely rotated in the sleeve C' in the adjustable jaw C, but is prevented from having any longitudinal motion therein by means of an upset or washer h', located at the inner end of said nut, adjacent to the inner end of the sleeve C' on the jaw C, as shown in Figs. 2 and 4. The outer end of the sleeve C' is held in contact with the under side of the adjuster or actuator H'. Consequently the jaw C and its sleeve C' are caused to move in and out relative to the shaft-iron B and its jaw b during the rotary adjustment of the actuator or lever H', as shown in Figs. 2 and 4.

To couple the thill to the bolt of the axle-clip, it is only necessary to place the jaw b over the thill-coupling bolt or its rubber sleeve and then turn the jaw C upon the sleeve C' as a pivot until it alines with the jaw b. The nut H is then screwed on the screw-threaded bolt b" by turning the actuator H' until the jaws C and b encompass the clip.

bolt D or its rubber sleeve and will thus be held firmly and securely thereon. To uncouple the device, this operation has merely to be reversed and the jaw C swung to a position diametrically opposite to that shown in the drawings.

This invention is very advantageous for several reasons, among which may be mentioned: The adjusting device is constructed 10 in such a manner as to be entirely protected from water, dirt, &c., whereby rusting and clogging of the parts are prevented. The screw of the adjusting device is not liable to bend or bind on account of the sleeve on the 15 adjustable jaw being guided in a socket or recess in the shaft-iron. By having the adjuster provided with one or more apertures adapted to be connected to the thill-coupling or shaft by means of a strap the adjuster is 20 prevented from turning loose, thus preventing the spreading of the jaws in which the thill-coupling bolt is journaled. By means of said screw-actuated adjuster the movable jaw may 25 be closed relative to the lower jaw and the coupling-bolt or its rubber sleeve with just as little force as necessary for accomplishing the desired result.

Having thus fully described the nature, construction, and operation of my invention, I 30 wish to secure by Letters Patent and claim—

1. In a shaft-shackle, the combination with the thill-iron terminating at its extremity in a jaw *b*, and provided on its inner face with

a threaded stud *b''*, of the interiorly-threaded sleeve H, engaging said stud and provided with an adjuster, and the jaw C, journaled on said sleeve and provided with an extremity adapted to encompass the bolt D, or its elastic cushion *d*, as set forth. 35

2. In a shaft-shackle, the combination with 40 the thill-iron terminating at its extremity in a jaw and recessed on its inner face, at *b'*, of a threaded stud *b''*, projecting from said recessed face, the interiorly-threaded sleeve H, engaging said stud and provided with an adjuster, and the jaw C, journaled on said sleeve, and provided with an extremity adapted to encompass the bolt D, or its elastic cushion *d*, as set forth. 45

3. In a shaft-shackle, the combination with 50 the thill-iron terminating at its extremity in a jaw *b*, and recessed on its inner face at *b'*, of a threaded stud *b''*, projecting from said recessed face, the interiorly-threaded sleeve H, engaging said stud and provided with an adjuster H', and means for connecting the latter to the shaft or thill-coupling and the jaw C, journaled on the sleeve H, adapted to encompass the bolt D, or its cushion *d*, as set forth. 55

In testimony whereof I have affixed my signature in presence of two witnesses.

SAMUEL R. BAILEY.
